UNITED STATES PATENT OFFICE.

MEREDITH LEITCH, OF POUGHKEEPSIE, NEW YORK, ASSIGNOR TO THE DE LAVAL SEPARATOR COMPANY, OF NEW YORK, N. Y., A CORPORATION OF NEW JERSEY.

SUPPORTING SPINDLE FOR CENTRIFUGAL MACHINES.

1,409,958.

Specification of Letters Patent. Patented Mar. 21, 1922.

Application filed November 11, 1919. Serial No. 337,282.

To all whom it may concern:

Be it known that I, MEREDITH LEITCH, a citizen of the United States, residing at Poughkeepsie, county of Dutchess, and State 5 of New York, have invented a new and useful Improvement in Supporting Spindles for Centrifugal Machines, of which the following is a full, clear, and exact description, reference being had to the accompanying 10 drawings, which form a part of this specification.

My invention relates to centrifugalizing machines and particularly to the spindles of such machines.

15 In the larger sizes of centrifugal separators, etc., the spindle is generally made in two pieces. The lower piece runs in two bearings and between them carries, in steam driven machines, a steam wheel, and in rope, 20 belt or worm and wheel driven machines, a pulley or worm. The upper piece, commonly called the bowl spindle, has its lower end in a socket on the top of the lower piece, carries the centrifugal bowl on its upper end 25 and is steadied by a bearing as high as possible under the bowl. When the bowl is not in perfect balance it causes a strong side thrust at the top of the spindle which, acting as a lever of the first class with the upper 30 steady bearing as a fulcrum, throws the top of the lower spindle sideways. With a reasonable overall height of machine it is impossible to make the part of the bowl spindle below the steady bearing and 35 above the socket on the lower spindle as long, relative to the part between the steady bearing and the bowl, as is desirable. The side pressure at the socket is, therefore, very great and the lower spindle, acting as 40 a lever of the second class with its lower bearing as a fulcrum, presses against its upper bearing with still greater force. These heavy pressures cause rapid wear of all 45 bearings.

The object of my invention is to provide a 50 spindle wherein lever relations will be such that the bearing pressures will be greatly reduced and yet retain the advantages due to a two-piece spindle.

55 In the accompanying drawings, which illustrate a preferred embodiment of my invention:

Fig. 1 is an elevation of one of my spindles for a steam driven machine with the 55 centrifugal bowl and the bearings in place.

Fig. 2 is a diagram illustrating the present lever construction and bearing pressures of a well known centrifugal separator mounted on a typical spindle of the prior art when the side thrust of the bowl is one hundred 60 pounds.

Fig. 3 is a similar diagram illustrating the lever proportions and bearing pressures for the same machine mounted on my improved spindle when the side thrust of the bowl is 65 the same.

Fig. 4 is a vertical sectional view of the machine showing the details of the bearings and supports.

Referring first to the construction shown 70 in Figure 1:

The centrifugal bowl *g* is carried on and driven by a bowl (or upper) spindle *h*, which is steadied at the top by a top yieldable or cushioned bearing *i* and at the bottom 75 by the upper bushing *j*. The top or steady bearing should be as high as possible on the bowl spindle and as near as possible to the bowl. The reduced lower end of the bowl spindle *h* enters a socket *l* in the upper 80 end of a lower spindle *k*. This socket is formed in an enlarged part of the lower spindle around which the hub of a steam wheel *m* is clamped. The lower end of the lower spindle turns in a bottom bushing *n* 85 and is supported by a thrust bearing consisting of a steel point *o* resting on tread wheels *p* running on a horizontal shaft carried in a step screw *r*. The bowl spindle carries above the upper bushing *j* a pair of worms *s* 90 for driving a speed indicator and governor not shown.

In order that the advantages of this spindle may be clearly apprehended, I have illustrated diagrammatically, in Figs. 2 and 3, 95 the difference between a typical spindle of the prior art and my improved spindle.

Referring to Fig. 2: *a'* is the center of gravity of the bowl and a side thrust of one hundred pounds is assumed to be exerted 100 against the spindle. *i'* is the center of the top bearing, where a resistance of 177 pounds must be exerted to hold the spindle. *l'* is the point where the bottom of the bowl spindle fits in a socket on the top of the lower 105 spindle and exerts a side pressure of seventy-seven pounds against the socket. At *j'* the lower spindle is guided by its upper bushing against which it presses with a force of 145 pounds and causes rapid wear. At *n'* the 110

lower end of the lower spindle is guided by a bottom bushing against which it presses with a force of sixty-eight pounds. o' is the thrust bearing that supports all revolving parts.

a^2 indicates the center of gravity of a bowl mounted on one of my improved spindles. i^2 is the center of the top bearing where the pressure is 148 pounds, a reduction of $16\frac{1}{2}\%$. $10 j^2$ is the upper bushing where the pressure will be only forty-eight pounds or less than one-third of that with the old type of spindle. l^2 is the point where the bottom end of the bowl spindle fits in a socket on the top of the lower spindle. Here there is no side thrust. n^2 is the bottom bushing that guides the lower end of the lower spindle and against which there is no side thrust. o^2 is the thrust bearing.

20 It will thus be seen that I have succeeded in greatly reducing the bearing pressures in the case of the upper bearing and the top bushing, and have eliminated the side thrust in the case of the lower bushing and the socket of the lower spindle.

Having now fully described my invention, what I claim and desire to protect by Letters Patent is:

1. In a centrifugalizing machine, in combination, a centrifugal bowl, a lower spindle, a bowl spindle mounted on the lower spindle, a bearing guiding the lower spindle, the upper end of the lower spindle being unsupported except by its engagement 30 with the bowl spindle, a bearing independent of the bearing for the lower spindle and non-yieldably guiding the bowl spindle near its lower end, and a spring-supported bearing independent of the other bearings and 35 guiding the bowl spindle relatively near its top.

2. In a centrifugal machine, in combination, a bowl, a lower supporting spindle and a bearing guiding it near its lower end, an 45 upper spindle supported by the lower spindle and supporting the bowl, and a plurality of bearings for the upper spindle which are independent of each other and of any bearing for the lower spindle and the upper only 50 of which is spring-supported and which are so positioned as to avoid substantial side thrust at the junction of the two spindles.

3. In a centrifugalizing machine, in combination, a thrust bearing, a lower spindle turning therein and supported thereby, a bearing for the lower spindle near its lower end, an upper spindle, a socketed connection 55 between the two spindles, the upper end of the lower spindle being otherwise unsupported,

ported, and a plurality of independent bearings each guiding solely the upper spindle, the lower bearing for the upper spindle being non-yieldable and the upper bearing for the upper spindle being yieldable, the two last named bearings being so positioned as 60 to minimize side thrust against them and substantially eliminate side thrust against the lower bearing and at said socketed connection.

4. Driving mechanism for the bowl of a 70 centrifugal machine comprising a two part spindle, a step bearing for the lower member of the spindle, a bearing sleeve for said member near the lower end, a bearing sleeve independent of any bearing for the lower 75 spindle member and guiding solely the upper spindle member above the upper end of the lower spindle member, a steady connection between the upper end of the lower spindle member and the lower end of the upper spindle member, and a steady bearing sleeve for the upper end of the upper spindle member independent of said bearing sleeve for its lower end.

5. A two part spindle for the bowl of a 80 centrifugal machine having a lower member and an upper member supported thereby, a pin and socket connection between the two members, a step bearing for the lower member, a bearing sleeve for the lower member 85 near the lower end thereof, two separate and independent bearing sleeves guiding solely the upper member of the spindle, the lower of the last two sleeves being entirely above the lower member of the spindle while the upper sleeve is just below the bottom of the bowl, and means for driving the lower member of the spindle.

6. In a centrifugal machine, in combination, a centrifugal bowl, a lower spindle, an 100 upper bowl spindle, and three bearings; one bearing carrying the lower end of the lower spindle, a second bearing non-yieldably guiding solely the lower end of the bowl spindle, and a spring-supported third bearing independent of the second bearing and 105 guiding the bowl spindle relatively near its top, the upper bowl spindle guiding the lower spindle whose upper end is otherwise unsupported, whereby the bearing pressures 110 at the upper and intermediate bearings are minimized and the side thrusts at the lower bearing and at the joint between the spindles are substantially eliminated.

In testimony of which invention, I have 115 hereunto set my hand, at Poughkeepsie, N. Y., on this 7th day of November, 1919.

MEREDITH LEITCH.
